Primary Examiner — Sheryl Lane*Assistant Examiner* — Leisha N Price*(74) Attorney, Agent, or Firm* — Jeenam Park(57) **CLAIM**

The ornamental design for a shovel, as shown and described.

DESCRIPTION

FIG. 1 is a front elevation view of a shovel, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a right side, front and top perspective view thereof;

FIG. 8 is a left side, rear and bottom perspective view thereof;

FIG. 9 is a right side, front and top perspective view thereof, shown in an alternative configuration;

FIG. 10 is a left side, rear and bottom perspective view of FIG. 9;

FIG. 11 is an exploded perspective view of FIG. 9, viewed from right side, front and top direction;

FIG. 12 is an enlarged view taken from indication circle 12 of FIG. 6; and,

FIG. 13 is an enlarged view taken from indication circle 13 of FIG. 11.

The broken lines in the drawings illustrate portions of the shovel and form no part of the claimed design. The dot-dash-dot broken line in the drawings forms no part thereof.
